UNITED STATES PATENT OFFICE.

FRANK E. BROWNE, OF LOS ANGELES, CALIFORNIA.

VERMIN-EXTERMINATOR.

SPECIFICATION forming part of Letters Patent No. 338,629, dated March 23, 1886.

Application filed December 21, 1885. Serial No. 186,309. (No model.)

To all whom it may concern:

Be it known that I, FRANK E. BROWNE, a citizen of the United States, residing at Los Angeles, in the county of Los Angeles and 5 State of California, have invented a new and useful Improvement in Vermin-Exterminators, of which the following is a specification.

My invention relates to that class of exterminators by means of which the vermin are 10 destroyed by forcing smoke into their burrows.

The object of my invention is to construct a cheap, simple, and convenient device by means of which the smoke can be forced into the burrows of the animals to be destroyed. 15 I accomplish this object by means of the device described herein and illustrated in the accompanying drawings, in which—

Figure 1 is a view of my device as it appears when the cylinder B is being raised. 20 Fig. 2 is a vertical cross-section, showing the valve D J pushed down upon the cylinder B, to close it and force it downward.

A is the furnace-cylinder, near the bottom of which is a grate, L, to sustain the fuel and fire. 25 B is the valve-cylinder, which fits thereon or therein, as may be desired.

D is a valve, of wood, having an iron facing, J, upon its under side and a cross-bar, E, with handles F at each end. The handles F 30 pass through iron loops G, secured to the valve-cylinder B, at the top thereof, and extending above the same such a distance as to give a vertical play of about half an inch to the handles F and the valve D J. The valve 35 is somewhat larger in diameter than the cylinder B, and juts out beyond the sides thereof, and the loops are bent outward from the top of the cylinder, so that the valve fits between them when it rests upon the top of the cylinder.

40 A bail, I, is pivoted to the furnace-cylinder A, at the middle thereof, and is of such length as to swing freely over either end thereof.

The manner of using my exterminator is as 45 follows: The furnace-cylinder A is placed over the open burrow Q, and earth is banked up around it. Straw or other suitable fuel is then placed in the cylinder above the grate L and ignited at the top. When burning well, the 50 furnace-cylinder is placed upon the top of the furnace-cylinder and pushed down by means of the handles and valve. The two cylinders

fit closely enough upon each other to require some slight pressure upon the upper one to force it down. As the valve is pressed down upon its cylinder to force it down, it closes the 55 end of the cylinder, thus inclosing the air contained in the two cylinders, and as the upper cylinder is pushed down the air-chamber formed by the two cylinders is shortened, and a portion of the air is forced down through 60 the burning straw into the burrow of the animal, carrying a cloud of smoke with it. When the valve-cylinder is depressed as far as it will go, the operator pulls upon the handles, thus raising the valve until the handles come into 65 contact with the top of the loops G, and leaving an opening at the top of the cylinder to admit the air. A further upward motion of the handles raises the valve-cylinder, the operator in the mean while holding his foot upon the 70 bail to hold the furnace-cylinder down. The operation of moving the valve-cylinder up and down forces the smoke-burdened air into 75 the burrow and suffocates the animal. When the fuel is exhausted, the machine is turned 75 up side down, thus throwing the fire into the valve-cylinder and upon the valve. The furnace-cylinder is then withdrawn from the valve-cylinder and placed upon the mouth of 80 the burrow and replenished with fuel. The fire is then poured out of the valve-cylinder upon the fuel in the furnace-cylinder, and the 85 operation before described is repeated.

It will be seen that by this device the first effect of an attempt to raise the valve-cylinder 85 by means of the handle is to open the valve, thus allowing the ingress of air as the cylinder is raised, while the first effect of an attempt to push down the cylinder is to close the end thereof, and prevent the egress of air. 90

The metal facing J upon the valve is provided to prevent the valve from burning; but the valve may be made wholly of either wood or metal, as may be desired. The cylinders are preferably of sheet metal. 95

The lower end of the furnace-cylinder may be funnel-shaped, to fit the burrow, as is customary in making such machines.

I am aware that two tubes sliding upon each other have heretofore been used for the purpose of expelling powder-charged air from the inside of such tubes, and do not claim such 100

construction as new; and do not claim the construction shown in the patent to Charles T. Jewett, No. 180,135, dated July 25, 1876.

Now, having described my invention, what 5 I claim as new, and desire to secure by Letters Patent, is—

1. The combination, in a vermin-exterminator, of two cylinders telescoping upon each other, loops secured to one of such cylinders, 10 and a movable valve secured to such cylinder by means of handles attached to such valve and extending therefrom through such loops, the loops allowing a play of the handles and valve

in the line of the axis of the cylinder, whereby the movement of the handles in operating the 15 machine will first operate the valve and afterward the cylinder.

2. In a vermin-exterminator substantially such as described, the combination of the movable valve D, handles F, loops G, and cylinder B. 20
